ELECTROTHERAPEUTIC ELEMENT

Louis Ludwig, Brooklyn, N. Y.

Application January 20, 1933, Serial No. 652,660

2 Claims. (Cl. 174—177)

The invention relates to an element to be used in an electric socket for generating either ultra violet or infra red rays, or both, for therapeutic purposes. It has for its main object to provide a unit containing all the parts necessary for the creation of such rays, and which may be operated by its mere insertion in a suitable electric socket or outlet. Another object is to provide means for not only compensating for the wear of the carbon electrodes employed, but also for providing sensitive means for correctly adjusting the distance between the tips of these electrodes. A further object is to provide an element of simple construction which can be installed and operated without any special skill required on the part of the user, which has no parts easily broken or apt to get out of order, and which can be manufactured at a low cost.

These and various other objects and advantages will be readily understood from the following description and from the accompanying drawing of a preferred embodiment of the invention in which, however, modifications may be made without departing from the scope of the appended claims. In the drawing

Fig. 1 is a side elevation of the element,

Fig. 2 a cross-sectional side elevation taken on line 2—2 in Fig. 1, and

Fig. 3 a top view.

Referring now to all the views, the element consists of a body member 10, made of insulating and heat-resisting material, which is preferably cone-shaped at its upper end 11 and provided with a threaded, metal ferrule at its lower end. Two oppositely-disposed seats 13 and 14 are molded on the upper end of the body member and in these seats holders 15 and 16 are secured by means of rivets 17 and 18. A carbon electrode 19 is secured in the holder 15 by a screw 20, while a carbon electrode 21 is inserted in a socket formed in the end of a screw 22 which is threaded in the holder 16. A hand wheel 23, made of insulating material, is secured on the screw to facilitate its manipulation.

A resistance coil 24 is wound in a spiral groove formed on the conical part of the body member. The lower end of this coil is connected to the ferrule by a lead 25, and the upper end 26 is secured under the head of the rivet 17. A bolt 27 is inserted through an opening 28 in the lower part of the body member. A lead 29, which connects the bolt with the holder 16, is clamped under the head of the bolt by a nut 30. This nut and the ferrule 12 constitute the electric terminals of the element.

The element functions in the following manner. When the ferrule 12 is inserted in a socket, a current will flow through this ferrule, through lead 25, resistance coil 24, end 26, rivet 17, holder 15; and, when the carbon electrodes are in contact with each other, through these electrodes and back through the holder 16, lead 29, and bolt 27 to the nut 30,—or vice versa. If the hand wheel 23 is then turned so that the tips of the electrodes are slowly separated, an arc will form between these tips. This arc gives off ultra violet rays.

When the infra red rays, given off by the resistance coil 24, are desired, the element is inserted in the socket of an ordinary parabolic reflector, so that these rays will be collected and reflected by the reflector. When used in this manner the carbon electrodes may be either spaced apart so as to utilize the ultra violet rays simultaneously with the infra red, or they may be in contact with each other so as not to arc and thus not give off any rays.

While I have shown the body member of a conical shape, it is evident that although such shape is preferable, it is not essential to the proper functioning of the device. In like manner, resistance elements other than spirally wound coils might be employed, and other means than the threaded ferrule might be used for attaching the element to a source of current.

From the foregoing it will be seen that this invention discloses a very simple, convenient, efficient and inexpensive appliance for accomplishing the results desired.

Having described my invention and its object, what I claim as new and wish to protect by Letters Patent is:

1. An element of the class described comprising an insulating and heating resisting cup-shaped body member having a rear extension, a threaded contact shell secured on said rear extension, a pair of oppositely-disposed and side-wardly-extending lugs formed on the outer end of the body member, a pair of electrode supports secured on said lugs, a pair of electrodes mounted in said supports, a resistance element spirally wound on the outside of the cup-shaped part of the body member, an opening formed centrally in the rear extension of the body member, a center contact secured in said opening, and the resistance element connected in series with the electrodes and with the threaded shell and the center contact.

2. An element of the class described comprising an insulating and heating resisting cup-shaped

body member having a rear extension, a threaded contact shell secured on said rear extension, a pair of oppositely-disposed and sidewardly-extending lugs formed on the outer end of the body member, a pair of electrode supports secured on said lugs, a pair of electrodes mounted in said supports, a resistance element spirally wound on the outside of the cup-shaped part of the body

member, an opening formed centrally in the rear extension of the body member, a center contact secured in said opening, the resistance element connected in series with the electrodes and with the threaded shell and the center contact, and manually operated means for separating the electrodes and varying the distance between them.

LOUIS LUDWIG.
